United States Patent [19]

Nishida

[11] Patent Number: Des. 307,724

[45] Date of Patent: ** May 8, 1990

[54] DEFECT INSPECTION DEVICE FOR SEMICONDUCTORS

[75] Inventor: Yoshiaki Nishida, Tokyo, Japan

[73] Assignee: Kabushiki Kaisha Toshiba, Kawasaki, Japan

[**] Term: 14 Years

[21] Appl. No.: 134,892

[22] Filed: Dec. 18, 1987

[30] Foreign Application Priority Data

Jun. 25, 1987 [JP] Japan 62-25627

CLAIM

The ornamental design for a defect inspection device for semiconductors, as shown.

DESCRIPTION

FIG. 1 is a front, top and left side perspective view of a defect inspection device for semiconductors showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof.

FIG. 1

FIG. 2

FIG. 3

FIG. 4

FIG. 5

FIG. 6

FIG. 7
